FENCE

Preston George Pierce, 1330 Brookhill Drive,
Fort Myers, Fla.

Filed Oct. 26, 1961, Ser. No. 67,266

Term of patent 14 years

(Cl. D28—1)

FIG. 1

FIG. 2

FIG. 4

FIG. 1 is a front elevation of a fence embodying my new design comprising a gate and two sections with the two fence sections being adapted to continue horizontally with similar sections in alternate arrangement to enclose any area.

FIG. 2 is a rear elevation of the fence,

FIG. 3 is an end view thereof; and

FIG. 4, a perspective of one of the posts of the fence.

I claim:

The ornamental design for a fence, as shown and described.
